HAIR SETTING DEVICE

Sanford Steve Kriesman and William Elliot Rosen, Philadelphia, Pa., assignors of twelve and two-thirds percent to Budd Granoff, New York, N. Y.

Continuation of application Serial No. 360,632, June 10, 1953. This application September 18, 1953, Serial No. 380,902

5 Claims. (Cl. 132—36)

The instant application is a continuation of our co-pending application Serial No. 360,632, filed June 10, 1953, and relates to a hair setting device and method of setting hair dry which constitute an improvement over the invention covered by our prior application.

The primary object of the present invention is to provide a hair setting device and method whereby heat is applied to a dry molded tress of hair while uniform tension is exerted on the entire molded tress and while the molded tress is restrained against distortion.

Another object of the invention is to provide a hair setting device in the form of a clamp having a heat generating means on one of its arms and a means associated with one of the arms to enter the center of the molded tress for the purpose of maintaining the tress in its proper molded position during the setting thereof.

A further object of the invention is to provide a hair setting device in the form of a clamp having a heat generating means on one of its arms, the initial relative positions of the arms being such that when they are opened to receive a molded tress, they extend substantially parallel to each other so that uniform tension is applied to the entire molded tress.

Another object of the invention is to provide a hair setting device of the character described which, in addition to being functional, is simple, inexpensive, attractive and easy to manipulate.

And yet another object of the invention is to provide a method of setting hair dry in which the molded tresses can be safely, completely and effectively set in so short a time that one can begin successively to remove the heat-producing clamps immediately after the last clamp had been applied to a tress.

These and other objects of the invention will become more apparent as the following description proceeds in conjunction with the accompanying drawing, wherein:

Figure 1 is a side elevational view of the hair setting device;

Fig. 2 is a top plan view thereof;

Figure 3 is a bottom plan view thereof and illustrating the manner in which a pin curl is retained therein;

Figure 4 is a perspective view of a chemical packet employed in the device;

Figure 5 is an enlarged longitudinal sectional view through the device; and

Fig. 6 is a diagrammatic perspective view of the device and illustrating the manner of applying an additional chemical therein.

Specific reference will now be made to the drawings wherein similar reference characters are used for corresponding elements throughout.

The present device, indicated at 10, is essentially a clamp with a heat-generating means associated therewith and including additional means, as will appear hereinafter, to retain a tress of molded hair in a firm and proper position during the setting thereof. The device comprises an upper arm 12 and a lower arm 14 which are provided adjacent their rear ends with cooperating

2

ears 16 and 18 carrying a pivot pin 20. A suitable spring 22 embraces the pivot pin and bears against the inner faces of the arms, as shown in Figure 5, to urge the arms into a closed position. The ends 24 and 26 of the upper and lower arms which bear on the spring 22 constitute the operating handle for the clamp.

Molded with or otherwise secured to the upper arm 12 is a container 28 to the top of which is hinged as at 30 a lid 32 for access to the interior of the container. The lid is provided with a plurality of vents 34 and a central aperture 36 for a purpose soon to appear. At its front end the lid includes a lip 38 adapted to snappingly and releasably engage a protuberance 40 on the container.

Press fit into the bottom of the container is a disk 42 which is limited in its inward movement by a peripheral shoulder 44 in the container wall. Depending centrally from the disk is a protuberance 46, preferably arcuate, for a purpose soon to appear.

At this point it should be observed that the arms, container and lid are preferably fabricated of a non-heat conductive material while the disk is fabricated of a heat conductive material. The non-heat conductive material may be any suitable plastic having a softening temperature above the maximum temperature generated in the container. The heat conductive material may be any suitable metal such as aluminum, brass, etc.

As shown in the drawings, the lower arm 14 is preferably trifurcated and includes a central member 48 joined by two arcuate members 50 and 52, the latter being peripherally contiguous with the margin of the container 28. The trifurcated arm presents a wide bearing surface for a molded tress of hair engaged in the clamp. The portion of the lower arm immediately beneath the disk 42 is normally upwardly inclined from the pivot 20 to the forward end of the container at a predetermined angle, as shown clearly in Figure 5 and for a purpose soon to appear.

Insertable in the container when the lid is open is a packet 54 which is adapted to rest upon the disk 42. The packet comprises a porous envelope 56, such as paper or cloth mesh, containing a chemical compound or compounds 58. In order that the packet lie flat upon and cover the entire inner surface of the metallic disk 42, it is preferred that a metallic foil 60 be provided to which is crimped and secured the porous envelope 56.

The compound 58 may be potassium or magnesium permanganate. To generate heat in the container for conduction through the metallic disk 42 to the clamped tress of hair, an additional chemical in liquid form can be dropped onto the packet 54 through the perforation 36 of the lid 32 by means of a dropper or a flexible squeeze bottle 60. Said chemical in liquid form may be glycerol which will react exothermally with the permanganate as set forth in the Bonat Patent No. 2,239,410. It will be understood that the contents of the packet and chemical to be added thereto is not limited to those chemicals disclosed in said Bonat patent. Any combination of chemicals may be employed provided they are safe, will not react with the materials from which the present device are fabricated and will react exothermally.

The present invention also comprises a novel method of setting hair dry employing the principles of the above described device. It comprises the clamping of a dry molded tress of hair and applying heat on the molded tress while the latter is subjected to uniform pressure or tension and while the tress is restrained against distortion.

The method is most efficiently carried out with the above described device as follows. The lid 32 is hinged to the open position and the packet 54 is inserted in the container 28, the latter resting on the metallic disk 42. The lid is then closed and the second chemical in

liquid form is dropped onto the packet through the central aperture 36 of the lid.

A tress of hair is then molded preferably in the form of a pin curl 62 and clamped, as shown in Figure 3, between the upper and lower arms 12 and 14. Because the initial position of the lower arm 14 is inclined upwardly away from the pivot point, it will be seen that, upon opening the clamp, the lower arm will assume a position substantially parallel to the upper arm, as shown in dotted lines in Figure 1. Thus the lower arm will exert uniform pressure or tension on the molded tress in the clamp. In addition, a pin curl always includes a central space or void 64. The protuberance 46 of the disk 42 enters this space to retain the pin curl in its proper molded condition while the latter is setting. The heat generated in the container, which usually does not exceed a maximum temperature of 180° F., is conducted through the metallic disk to the clamped tress of hair and sets the hair within a matter of five to ten minutes without the need for prior wetting of the hair.

The trifurcation of the lower arm 14 permits the arm to present a wide bearing surface on the molded tress. This together with the fact that the lower arm assumes a position substantially parallel to the upper arm and the fact that the protuberance 46 enters the space 64 of the pin curl permits the curl to be retained in its proper molded condition throughout the entire setting operation.

Since the heat generated in the clamp is sufficient to set the molded tress in approximately five to ten minutes, one can begin to remove the first and subsequent clamps immediately after the last clamp has been applied to the hair.

While a preferred embodiment of the invention has been shown and described hereabove, minor variations thereof may be made without departing from the spirit of the invention and the scope of the appended claims. Thus, while it has been found that "Plexiglas V," a thermoplastic acrylic polymer resin, serves effectively as a non-heat conductive material from which the device can be fabricated, any other plastic may be employed provided that it has a softening temperature in excess of the maximum temperature generated in the container.

We claim:

1. A hair setting device comprising a clamp having a pair of pivoted spring-tensioned arms adapted to receive therebetween a tress of hair in the form of a pin

curl, a container mounted on the outer surface of one of said arms and adapted to retain a heat generating means therein, and a disk carried at the bottom of said container above the other of said arms, said disk including a protuberance adapted to enter the center of the pin curl and retain the same in its proper position during the setting operation.

2. The combination of claim 1 wherein said clamp and container are fabricated of non-heat conductive material and said disk is fabricated of heat conductive material.

3. A hair setting device comprising a clamp having a pair of upper and lower arms pivoted adjacent one of their ends and including spring tension means to urge the arms into a closed position, said one end of said arms constituting an operating handle to open said arms, a container mounted on the outer surface of said upper arm between the pivot point and the end of said upper arm opposite the handle, and heat generating means in said container, the portion of said lower arm beneath said container being inclined upwardly away from the pivot point to permit opening of said portion of said lower arm to a position substantially parallel to the portion of said upper arm carrying the container whereby uniform tension is applied to the tress of hair clamped between said arms.

4. The combination of claim 3 and a disk carried at the bottom of said container, said disk including a protuberance adapted to enter the center of the pin curl to retain the latter in proper position during the setting thereof.

5. The combination of claim 4 wherein said clamp and container are fabricated of non-heat conductive material and said disk is fabricated of heat conductive material.
